LANTERN

Nolan K. Rhoades, Beloit, and John V. Hansen, Madison, Wis., assignors to The Electric Storage Battery Company, Philadelphia, Pa., a corporation of New Jersey

Application April 3, 1958, Serial No. 50,324

Term of patent 14 years

(Cl. D48—24)

FIG. 1

FIG. 2

FIG. 3

FIG. 4

Fig. 1 is a side elevational view of a lantern showing our new design;

Fig. 2 is a front elevational view thereof;

Fig. 3 is a rear elevational view thereof with the base omitted in part for convenience of illustration; and

Fig. 4 is a sectional view looking the direction of the arrows 4—4 of Fig. 1.

The dominant features of our design reside in the portions shown in full lines.

The side of the lantern not shown is substantially the same in appearance as the side shown.

We claim:

The ornamental design for a lantern, as shown and described.
